UNITED STATES PATENT OFFICE.

HEINRICH MÜLLER, OF GROSS FLOTTECK, NEAR HAMBURG, GERMANY, ASSIGNOR TO
THE FIRM JOHANN CÄRL MÜLLER, OF DRESDEN-A., GERMANY.

MACHINE FOR MECHANICALLY MIXING TOBACCO LEAVES.

Application filed December 24, 1926, Serial No. 156,851, and in Germany November 7, 1925.

This invention relates to devices for mechanically mixing tobacco leaves, and has for its object to provide an improved device of this character.

All the operations for mixing tobacco leaves, especially in the cigarette and smoking tobacco industries were hitherto performed manually, generally by female operatives, and this resulted amongst other disadvantages in the particularly objectionable disadvantage that the tobacco leaves had to be repeatedly and frequently handled. This method of mixing is, therefore, very unhygienic, and moreover considerable quantities of tobacco were hitherto lost. Furthermore, the leaves on account of their frailty are readily broken or split and the process of mixing manually is very lengthy and wearying.

20 The invention has for its main object to obviate these disadvantages and moreover provides for absolutely uniform mixing of the various kinds of tobacco.

In the accompanying drawings, Figure 1 is a side elevational view of a preferred constructional form of the invention,

Figure 2 being a plan view thereof.

Referring now to the drawing a number of sorting tables 1, 2, 3, 4, 5 etc. at which the operatives are seated on stools *a*, are provided, and the various kinds of tobacco are brought up to the tables in boxes *b*, the tobacco to be separated being removed from them and placed on the tables. An operative is seated on each side of each box *b* and each box is, therefore, always attended to by two operatives. Apertures *c* are provided in the tables, the separated tobacco being pushed towards these apertures, so that it falls through the apertures to conveying bands *d*, which pass over conducting rollers *e* and *f* at the ends of the tables. These bands are operated by a motor *M*, through gear wheels *g*, *h*, and a shaft *i*, which carries the rollers *e*. The bands *d* are arranged adjacent to a common collecting and conveying band *k* running transversely thereto, which conveys the already mixed tobacco to the left as shown in the drawing, to an upwardly inclined conveying band *l* and a horizontal conveying band *m* at the upper end thereof.

The conveying band *k* passes over the

rollers *n*, *n'* and the upwardly inclined conveying band *l*, passes over rollers *o*, *o'*, the horizontal conveying band *m* passing over the rollers *p*, *p'*. These rollers are driven by a motor *M'* by means of a belt *r* on the shaft of the roller *o*, and thence by means of a chain *s*, co-operation with chain wheels on the axes of the rollers *o*, *n'*, *o'*, *p'*.

From the horizontal endless band *m* the tobacco is delivered to a conveying band *t*, which can be agitated in a horizontal plane and which, upon agitation, delivers the tobacco into a main funnel *u*, in such a manner that the tobacco is uniformly distributed over the surface of the funnel. A vertical channel *u'* of the funnel opens over funnel mouths *v* in a cylinder *w* capable of being rotated in a horizontal plane, the funnel mouths *v* being connected in series so that when the cylinder is rotated no tobacco is lost, as all the funnels communicate directly with one another. Below the funnel mouths *v* chambers are provided in the cylinder *w*, boxes *x* being disposed in the chambers in such a manner that there is a box *x* below each funnel mouth. The cylinder *w* is secured to a shaft *y* and is pivotally mounted in the bearing *z*, the shaft *y* being driven by a motor *M* through bevel gearing *z*, *z'*.

In operation the various kinds of tobacco are deposited on the conveying bands *d* through the apertures *c*, which deliver the tobacco to the common conveying band *k*, whence it is conveyed upwards to the funnel *u* in an already mixed condition, the different kinds of tobacco being proportioned according to the recipe of a given mixture, on the tables 1, 2, 3, 4, 5. The movement of the boxes *x* under the funnels *u*, *u'* is arranged to take place at such a speed that only a thin layer containing the prescribed proportions of each kind of tobacco drops into each box each time it passes under a funnel mouth *u'*, so that the boxes are filled with a number of layers of mixture (several hundred, for example), and an intimate mechanical mixture is consequently obtained. The boxes *x* after being completely filled are removed from the cylinder *w* and placed directly in a tobacco cutting machine. It will, therefore, be evident that by using the improved mixing device the hands of the operatives come into contact with the tobacco

once only, that is to say when separating the leaves from the bales and pushing them towards the apertures *c*.

Having now described my invention what I claim as new and desire to secure by Letters Patent, is:—

1. In a machine for automatically mixing tobacco leaves, a plurality of individual conveyors each adapted to carry a different brand of leaves, a common conveyor onto which the different brands of leaves are deposited from said individual conveyors, a stationary funnel shaped chute at one end of said common conveyor to receive the mixture of different leaves from the latter and a series of individual receptacles moving past said stationary receptacle so that the leaves are distributed therein from the latter in uniform successive layers.
2. In a machine for automatically mixing tobacco leaves, a plurality of individual conveyors each adapted to carry a different brand of leaves, a common conveyor onto which the different brands of leaves are deposited from said individual conveyors, a stationary funnel at one end of said common conveyor to receive the mixture of different leaves from the latter and a series of revolving receptacles adapted to successive-

ly register with said funnel and thereby cause said leaves to be uniformly stacked therein in successive layers.

3. In a machine of the character described as per claim 1 in which in extension of said common conveyor an auxiliary conveyor is provided capable of oscillation across said stationary receptacle to cause the leaves falling into the latter to be uniformly distributed therein.

4. In a machine of the character described, a plurality of tables or platforms each having recesses, a plurality of individual conveyors receiving different brands of leaves through the recesses of the different tables, a common conveyor receiving the different brands of leaves from the individual conveyors, a stationary funnel shaped chute at one end of said common conveyor and a revolving casing formed with a series of contiguous funnel shaped chutes and adapted to carry removable receptacles, said chutes being adapted to register successively with said stationary chute so that the leaves are distributed in said receptacles from the latter in uniform successive layers.

In testimony whereof I affix my signature.

HEINRICH MÜLLER.
